Patented May 11, 1976

239,884

HAIR DRYER

Petrus Jacobus Johanna Nagelkerke, Drachten, Netherlands, assignor to U.S. Philips Corporation, New York, N.Y.

Filed July 17, 1974, Ser. No. 489,353

Claims priority, application Switzerland Feb. 8, 1974

Term of patent 14 years

Int. Cl. D28—03

U.S. Cl. D86—10 F

FIG. 1 is a perspective view of the hair dryer showing my new design;

FIG. 2 is a right side elevational view thereof;

FIG. 3 is a left side elevational view thereof;

FIG. 4 is a front elevational view;

FIG. 5 is a rear elevational view;

FIG. 6 is a top plan view; and

FIG. 7 is a bottom plan view.

I claim:

The ornamental design for a hair dryer, as shown and described.
